UNITED STATES PATENT OFFICE.

BASCUM O. AUSTIN, OF WILKINSBURG, PENNSYLVANIA, ASSIGNOR TO WESTINGHOUSE ELECTRIC & MANUFACTURING COMPANY, A CORPORATION OF PENNSYLVANIA.

CONTROL APPARATUS.

Application filed October 6, 1919. Serial No. 328,848.

My invention relates to control apparatus and particularly to unit switches for use in railway control systems and the like.

One object of my invention is to provide a switch of the above-indicated character having a novel movable contact device whereby a desirable rolling and wiping contact is provided through the agency of a simple and reliable mechanism.

More specifically stated, it is one object of my invention to provide a movable contact mechanism for a unit switch wherein a lost-motion connection with a stationary supporting member is provided at an intermediate point of the movable switch arm, the outer ends of which are respectively provided with a contact tip and a biasing spring, while the power-actuated means is secured to a second intermediate point of the switch arm.

Another object of my invention is to provide integral means for performing the function of both a contact-tip holder and a double arcing horn, this construction applying to both the stationary and the movable contact tip.

My invention may best be understood by reference to the accompanying drawing, wherein—

Figure 1 is a view, chiefly in section and partially in elevation, of a portion of a unit switch constructed in accordance with my present invention; and

Fig. 2 to Fig. 7, inclusive, are various elevational views of certain parts of the structure that is illustrated in Fig. 1.

Referring to the drawing, the structure here shown comprises a suitable insulating base or supporting means 1, a stationary contact device 2, a co-operating movable contact device 3 and a portion of the power-operated means 4 for the switch.

The stationary contact device 2 comprises a contact-tip holder 6 which is best shown in Fig. 5, Fig. 6 and Fig. 7 and which is secured to the base or supporting means 1 of insulating material by means of a screw 7 that is fitted into the main body portion 8, into which a large tap bolt 9 also extends, such bolt forming a portion of the main switch terminal for connection to an external circuit, in accordance with customary practice. The body portion 8 is provided with a pair of triangular depending lips or

flat lugs 10 and 11, to act as arcing horns, 55 and also with a downwardly extending ear 12 on the rear side, to which the familiar bent contact tip 13 is secured by a bolt 14.

It will be seen that, in addition to performing the function of a contact-tip holder, the member 6 is provided with the pair of integral arcing horns 10 and 11 that are placed in close proximity to, and on opposite sides of, the contact tip proper 13. The configuration of the arcing horn members 65 10 and 11 is such as to provide the desired rapid dissipation of arcs that are formed by the separation of the stationary and movable contact tips.

The movable contact device 3 comprises 70 a shank or arm 15 which embodies, near its outer end, a solid or body portion 16 to which the contact tip 17 is secured by means of a bolt 18. The arm 15 is also shown in Figs. 2, 3 and 4. Integrally formed with 75 the body portion 16 are a plurality of upwardly extending lips or lugs 19 and 20 that are so related to the contact tip 17 and are of such configuration that the customary functions of arcing horns are effectively secured. An integral curtain or lug 21 extends downwardly for the purpose of deflecting any arcs from the lower portions of the unit switch including the power-actuated device 4.

A pair of integral apertured ears 22 extend downwardly from an intermediate point of the switch arm 15 for the purpose of mechanical connection to the power-operated means 4, as subsequently more fully described. The intermediate portion of the arm 15 is apertured vertically, as indicated at 15^a, and, near the right-hand end of the arm, a slotted portion 23 is provided for forming a part of a lost-motion connection, 95 while the arm terminates in a lug or boss 24 integrally secured to the lower end of the slotted portion 23 for a purpose to be set forth.

A pin or small rod 25 passes through the 100 slotted portion 23 and is suitably secured to the side walls of a box or hollow block 26, only one-half of which is shown in the sectional view of Fig. 1. A coil spring 27 is, in part, located within the box 26, acting between the lug 24 and a boss 28 on the underside of the upper solid portion 29 of the box 105 26, which portion is secured to a supporting

block 30 by means of a suitable bolt 30^a. The block 30 is fastened to the base 1 in the same manner as the contact holder 6, as will be understood without further exposition.

5 A braided or stranded shunt 31 has one end secured by a bolt 32 that extends into the body portion 16 of the switch arm 15, the shunt curving beneath the box 26 and having its other end fastened to a contact clip 33 which is held in position by the bolt 30^a. Consequently, the current is shunted from the contact block 30 through the shunt 31 to the body portion 16 of the switch arm 15, whereby the lost-motion connection members 25 and 23, as well as the spring 27, are relieved of the necessity of carrying current.

10 The power-operated means 4 may be of any familiar type, such as the solenoid or, preferably, the pneumatic actuating mechanism that is well-known in the prior art, and the upper portion shown comprises a hook member 34 which passes over a pin 35 that is secured between the ears 22 of the switch arm 15. A suitable insulator 36 is attached to the hook 34 and a metallic member 37 is directly attached to the piston stem (not shown) or other power-operated member, as will be understood.

15 20 The mechanical operation of my switching device may be briefly set forth as follows. Upon the application of power to the insulator member 36, the switch arm 15 moves upwardly, swinging around the pin 25 as a center until initial contact is effected between the contact tips 17 and 13. Continued upward movement of the insulator 4 then effects a rolling action of the movable contact tip 17 across the face of the stationary contact tip 13 by reason of the lost-motion connection 25 and the opposing force that is exerted by the spring 27. In the final closed position of the contact members, the right-hand flat surfaces of the contact tips are in close engagement, while the slotted portion 23 of the switch arm has been moved upwardly to its limiting position with respect to the pin 25.

25 30 When the power-operating means 4 is released, the opposite mechanical action takes place, as will be understood, and, at the same time, the integral lips 10 and 11 on the stationary contact holder 6 and the integral lips 19 and 20 on the movable switch arm 15 serve the function of arcing horns to rapidly and harmlessly dissipate the arcs that are formed by the separating contact tips.

35 40 An arc drawn between the contact members 13 and 17 is forced outward and delivered to the arc horns. Since both of the arc horns are provided with spaced lips, the ends of the arcs are concentrated and prevented from spreading. Further, by making the arc horns substantially trough-

45 shaped, gases formed during the arc-rupturing process are prevented from flowing backward under the influence of a magnetic field set up by the looping of the arc.

50 It will also be readily understood that the depending curtain 21, carried by the lower arc horn, will serve to prevent an arc which tends to travel backward on the under face of the arc horn from reaching the insulator 4.

55 It will be appreciated that by reason of the relatively heavy construction of the integral arcing horns, a long life thereof will result.

60 I do not wish to be restricted to the specific structural details or arrangement of parts herein set forth, as various modifications thereof may be made without departing from the spirit and scope of my invention. I desire, therefore, that only such limitations shall be imposed upon my invention as are indicated in the appended claims.

65 I claim as my invention:

70 1. A contact holder for unit switches having a plurality of parallel-extending arcing horns joined substantially throughout their lengths integrally secured thereto.

75 2. A contact holder for unit switches having a tip-receiving portion and a plurality of integral arcing horns located on opposite sides of the contact tip said horns being joined substantially throughout their lengths.

80 3. A contact holder for unit switches having a body portion and an integral bifurcated portion shaped like a trough for functioning as a double arcing horn.

85 4. A unit switch comprising a stationary and a co-operating movable contact member respectively embodying contact tips and contact holders having integrally formed lips located near said tips and in the plane thereof to act as arcing horns.

90 5. A unit switch comprising a stationary and a co-operating movable contact member respectively embodying body portions, contact tips secured thereto, and bifurcated portions integrally formed with said body portions to act as double arcing horns for said tips.

95 6. A switching device comprising, in combination, cooperating stationary and movable switch members, contact tips shaped to permit the making of a rolling and wiping contact carried by said switch members, means adapted to operate the movable member to effect a rolling and wiping contact between said tips, and arcing horns disposed to receive an arc from the contact tips, each arcing horn being provided with a plurality of spaced tips disposed thereon to form substantially a trough.

100 7. A switching device comprising, in combination, cooperating stationary and mov-

- able switch members, contact tips shaped to permit the making of a rolling and wiping contact carried by said switch members, means adapted to operate the movable member to effect a rolling and wiping contact between said tips, and arcing horns disposed to receive an arc from the contact tips, each arcing horn being provided with a plurality of spaced lips disposed thereon to form substantially a trough, said lips being shaped to present substantially pointed projections adjacent the contact tips.
8. A switching device comprising, in combination, cooperating stationary and movable switch members, contact tips shaped to permit the making of a rolling and wiping contact carried by said switch members, means adapted to operate the movable member to effect a rolling and wiping contact between said tips, and arcing horns disposed to receive an arc from the contact tips, each arcing horn being provided with a plurality of spaced lips disposed thereon to form substantially a trough, said lips being shaped to present substantially pointed projections adjacent the contact tips, said contact tips extending beyond said projections thereby to deliver arcs to the outer portions of said arcing horns.
- 36 9. A switching device comprising, in combination, cooperating stationary and movable switch members, contact tips shaped to permit the making of a rolling and wiping contact carried by said switch members, means adapted to operate the movable member to effect a rolling and wiping contact between said tips, and arcing horns disposed to receive an arc from the contact tips, each arcing horn being provided with a plurality of spaced lips, the inner faces of said lips diverging as they extend outwardly from said contact tips.
10. A switching device comprising, in combination, cooperating stationary and movable switch members, contact tips shaped to permit the making of a rolling and wiping contact carried by said switch members, means adapted to operate the movable member to effect a rolling and wiping contact between said tips, arcing horns disposed to receive an arc from the contact tips, each arcing horn being provided with a plurality of spaced lips and an arc deflecting curtain carried by one of said switch members cooperative with an arcing horn.
11. A switching device comprising, in combination, cooperating stationary and movable switch members, contact tips shaped to permit the making of a rolling and wiping contact carried by said switch members, contact tips shaped to permit the making of a rolling and wiping contact carried by said switch members, each arcing horn being provided with a plurality of spaced lips, the inner faces of said lips diverging as they extend outwardly from said contact tips, each arcing horn being provided with a plurality of spaced lips, the inner faces of said lips diverging as they extend outwardly from said contact tips, and an arc deflecting curtain carried by one of said switch members.
12. A switching device comprising, in combination, cooperating stationary and movable switch members, contact tips shaped to permit the making of a rolling and wiping contact carried by said switch members, means adapted to operate the movable member to effect a rolling and wiping contact between said tips, and arcing horns disposed to receive an arc from the contact tips, said arcing horns being spaced from the contact tips, each arcing horn being provided with a plurality of spaced lips, the lips of said arcing horns being shaped to present substantially pointed projections adjacent the contact tips, said contact tips extending beyond said projections thereby to deliver arcs to the outer portions of said arcing horns.
13. A switching device comprising, in combination, cooperating stationary and movable switch members, contact tips shaped to permit the making of a rolling and wiping contact carried by said switch members, means adapted to operate the movable member to effect a rolling and wiping contact between said tips, and arcing horns disposed to receive an arc from the contact tips, each arcing horn being provided with a plurality of spaced lips disposed thereon to form substantially a trough, said lips being disposed on opposite sides of corresponding contact tips.
14. A switching device comprising, in combination, cooperating stationary and movable switch members, removable contact tips shaped to permit the making of a rolling and wiping contact carried by the switch members, means adapted to effect the rolling and wiping contact of said tips, bifurcated arcing horns formed integral with the switch members and disposed to receive an arc from the contact tips, the inner faces of the bifurcated portions diverging as they extend outwardly, thereby adapting said horns to effect the function of a double arcing horn.

In testimony whereof, I have hereunto subscribed my name this 4th day of Oct. 1919.

BASCUM O. AUSTIN.
